FURNACE CONSTRUCTION, INCLUDING
PORTABLE WALL PANEL

Raymond E. Over, Mokoma, Ill., assignor to M. H. Detrick Company, Chicago, Ill., a corporation of Delaware

Application December 13, 1954, Serial No. 474,809

2 Claims. (Cl. 110—1)

This invention relates to a portable furnace panel comprising refractory brick and associated supporting structure which may be prefabricated and installed as a unit in a new or old furnace wall or arch.

The portable panel of the invention is suitable for wall portions of an open hearth furnace such, for example, as a lintel over a charging door, a load bearing uptake wall support, or a pier between charging doors. It also is suitable for other wall portions and for wall or arch portions of other types of furnaces, as will be seen.

Open hearth and other large, high temperature furnaces usually are operated continuously until some major component, such as the main arch, either fails or is in immediate danger of failure. To so operate such a furnace it is necessary to repair some portions of the furnace arch or walls during the campaign period. This repair work is performed by special "hot gangs" trained to make brick-work repairs in a minimum length of time. Repair operations that would be comparatively simple at ordinary temperatures present many problems at steel-making temperatures.

One object of the invention is to provide a prefabricated portable panel which quickly can be installed in a furnace mainly by means of mechanical equipment.

Another object is to provide a prefabricated portable panel which is suitable for use in new or old furnaces. Suitable panel supporting means easily may be incorporated in the design of a new furnace and they readily may be applied to the existing superstructure of an old furnace.

Another object is to provide a panel particularly suitable for repairing certain short-lived portions of a furnace wall such, for example, as a lintel over a charging door or a pier between charging doors. These wall portions, as will be understood, are subject to deterioration from the physical acts involved in charging the furnace as well as from the destructive action of high temperature gases.

Another object is to provide a prefabricated portable panel which when installed has substantial load bearing characteristics so that it is capable of giving vertical support to a number of superposed rows of refractory brick. This feature of the panel is particularly valuable when the panel is used in the upper portion of a wall adjacent the marginal edge of a flat arch, as in the case of a lintel over a charging door in an open hearth furnace. In such application the portable panel supports several tiers of refractory brick which fill the space between the top of the refractory brick in the panel and the adjacent marginal edge of the flat arch.

Another object of the invention is to provide a simple, inexpensive brick retainer which cooperates to secure in position the refractory brick used in the panel.

Still another object is to provide a prefabricated portable panel which uses only a few simple component parts and which incorporates standard-shape refractory brick. The panel may be fabricated at a remote location or under desirable conditions at the furnace site and easily transported to the place of installation.

2

When subject portable panels are installed as original equipment, subsequent replacement when necessary is particularly simple, although the design is such that the panel is installed easily in existing furnaces.

5 Other objects, advantages and features of the invention will be apparent as the description proceeds, reference being had to the accompanying drawing wherein two forms of the invention are shown. It is to be understood that the description and drawing are illustrative only and that the scope of the invention is to be measured by the appended claims.

In the drawing:

Fig. 1 is a front elevational view of a portable furnace panel embodying the invention, the panel being shown mounted with respect to a pair of spaced furnace columns;

Fig. 2 is a top plan view of the panel shown in Fig. 1, the view being taken on line 2—2 through the furnace columns;

Fig. 3 is an enlarged sectional view on line 3—3 of Fig. 1, certain components being shown in dotted line because they are located to the right of the section line;

Fig. 4 is a sectional view on line 4—4 of Fig. 3;

Fig. 5 is a view, partly in section, of a modified form 25 of panel illustrating application thereof to a furnace wall adjacent the marginal edge of a flat arch, and

Fig. 6 is a perspective view of an element forming part of a brick retainer used in the panel.

Referring now to Figs. 1 and 2 of the drawing, the numerals 10 and 11 designate vertical columns in the steel 30 superstructure which surrounds and supports the walls and arch of a furnace. A transverse panel-supporting member 12 extends horizontally between columns 10 and 11, the ends of member 12 being welded or otherwise suitably secured to the columns.

35 A portable panel 15 embodying the invention comprises a mounting structure including a backing means 16 of predetermined size and shape. In the form of the invention shown, backing means 16 is a metal plate of rectangular shape, the plate being disposed in a generally vertical plane.

The mounting structure also includes a pair of horizontally extending, vertically spaced upper and lower angle members 17 and 18, respectively. One leg of each angle member is secured as by welding to the front face of 45 backing means 16 while the other leg extends in a direction normal to the front face of backing means 16, as best shown in Fig. 3. In some applications upper angle member 17 may be eliminated, if desired.

The one or two angle members 17 and 18 each constitutes a forwardly extending flange on backing means 16. These flanges, as will be seen, function, in the case of angle member 18, to provide vertical support for refractory brick contained in the panel and, in the case of angle member 17, to support both panel and superposed 55 brick and to aid in supporting the panel.

Means are provided for supporting the panel in position in a furnace wall and, in the form illustrated, such means comprise a pair of spaced hook-like members 20 and 21, best shown in dotted lines in Fig. 3. Members 60 20 and 21 are mounted, as by welding, to the top of backing means 16 and to angle member 17 if the latter be provided. Transverse member 12, previously mentioned, is received within hook recesses 22 to thus support the panel, backing means 16 of the panel lying flush against columns 10 and 11.

A lifting lug 25 having an aperture 26 may be provided at the top central portion of the mounting structure, as best shown in Fig. 1.

The front face of the mounting structure carries a plurality of horizontally and vertically spaced brick retainers 28, each comprising an elongated member 30 (Fig. 6) having a transverse aperture 31 at one end. A rod 32

3
is mounted symmetrically in aperture 31 as shown in Fig. 4.

In the form of the invention shown, a brick retainer 28 includes a threaded stud 33 secured at one end to the mounting structure. In some cases studs 33 are welded or otherwise secured to backing means 16 and in other cases to the legs of angle members 17 and 18 which are connected to backing means 16, as shown in Fig. 3. Elongated member 30 has an internally threaded axial bore 34 (Fig. 6) which receives the threaded end of stud 33. With this arrangement brick retainer 28 is somewhat adjustable in order to provide compensation for variation in the dimensions of brick associated with the retainers.

Three tiers or rows of refractory brick are shown mounted in the illustrated panel. The outside (upper and lower) rows are made up of brick 36 and 37 while the center or inside row is made up of brick 38. Brick 36, 37 and 38 have standard shapes including, in the case of brick 36 and 37, relieved portions to accommodate the flanges or legs of angle members 17 and 18 and recesses at the inner brick ends to accommodate brick retainers. As best shown in Fig. 4, a brick retainer 28 is received in recesses 40 and 41 respectively provided in each of an adjacent pair of brick. Retainers 28 are effective to hold the individual brick in position in the panel.

When a panel is fabricated at substantial distance from the point of installation it usually is desirable to secure the bricks together laterally by means of a steel band encircling the assembled brick. Such a band is shown in dotted line at 42 in Fig. 2.

Referring to Fig. 5, a portable panel 45 is shown mounted in a furnace wall adjacent the marginal edge of a flat arch generally designated 46. It is to be noted that marginal edge 47 of arch 46 is in general alignment with inner face 48 of panel 45 which in turn is in general alignment with the furnace wall below the panel. The wall below panel 45 is shown in dotted outline in Fig. 5 and designated 50. It is also to be noted that wall 50 has an upper termination somewhat below the plane of inner face 51 of arch 46.

Panel 45 is disposed in the wall space between the upper termination of wall 50 and the plane of inner face 51 of arch 46, as shown in Fig. 5. Backing means 53 of panel 45 extends somewhat above the top of the third brick row of panel 45 and is provided with hook members 54 to engage a transverse member 12 extending between wall columns.

The space between the top of the upper row of brick

forming part of panel 45 and the marginal edge 47 of arch 46 contains several rows of brick all of which are supported by panel 45. Five rows of such brick 55 are shown in Fig. 5 as well as a layer of insulating material 56 and an expansion joint 57. Fig. 5 thus is illustrative of one of many possible applications for a portable panel constructed according to the invention.

From the above description it is thought that the construction and advantages of my invention will be readily apparent to those skilled in the art. Various changes in detail may be made without departing from the spirit or losing the advantages of the invention.

Having thus described my invention, what I claim as new and desire to secure by Letters Patent is:

15 1. In a furnace having an arch and a wall adjacent one marginal edge thereof, said arch terminating in general alignment with the inner face of said wall and said wall terminating below the plane of the inner face of said arch, the combination of a portable wall panel disposed in part in the wall space between the top of said wall and said plane, said panel comprising mounting structure including backing means and a horizontal flange extending inwardly along the lower edge of said backing means, a plurality of horizontally and vertically spaced brick retainers mounted on the inner face of said mounting structure and vertically adjacent horizontal rows of refractory brick carried by said mounting structure and engaging said brick retainers, a row of said brick engaging said flange and being vertically supported thereby.

20 2. The combination of claim 1 with the addition of vertically adjacent horizontal rows of brick supported by the upper brick row of said portable wall panel and filling the space between the upper brick row of said wall panel 25 and the marginal edge of said arch.
